[57] ABSTRACT

A durable float which in a preferred embodiment includes polyurethane filled automobile tires including an attaching rod extending through the center of each polyurethane mass through the center of each tire, with the plurality of the polyurethane filled tires joined between their respective bases and joined between their respective top surfaces with any desired deck structure mounted on top of the joining-structures, each polyurethane-filled-tire unit being spaced from other units at predetermined intervals sufficient to avoid collection of floating debris, to give the desired live load.

FLOATING SPACE FRAME

This invention relates to floating platform for use in any large body of water, characterized by a high degree of both flexibility of design and durability of floatation means, while concurrently improving ecology.

Prior to this invention, there have been a variety of floating platforms alone or in conjunction with piers or the like. The structures of these floating platforms are generally complex in structure, made out of expensive building materials, involved and costly in their manufacture, cumbersome, unwieldy when constructed as a platform, restricted in design of floats and/or marinas, subject to corrosion and/or deterioration from environmental waters and/or weather conditions, lacking adequate reinforcing or support structures for the deck, and the like.

Objects of this invention include the overcoming and/or reducing of one or more of the above discussed problems, together with other objects apparent from the preceding and following disclosure.

One or more of the above objects are obtained by a floatation device of this invention which includes one or more floatation means, preferably in combination with and including a deck structure supported by a plurality of the separate floatation means spaced at predetermined intervals distant from one another with the plurality of floatation means being joined to one another between their respective bases by rigid joining structures and between their respective upper portions by additional joining structures.

The figures:

FIG. 1 is a perspective view of a typical embodiment of a space frame of this invention floating within a body of water, moored to a plurality of pilings.

FIG. 2 is a cross sectional view taken along line 2—2 of FIG. 1, of a preferred floatation device of this invention and of the upper and lower supports (shown in part) typically employed for connecting the bottom portions thereof to the bottom portions of one or more distantly spaced other floatation means and for connecting the upper portions thereof to the upper portions of other distantly spaced floatation means, the upper connecting means illustrated also including a deck.

FIG. 3A illustrates in cross sectional view a typical mechanism employed in the process of this invention, namely the mounting of a tire on a turntable driven by a motor with a rod means centrally mounted on the turntable and with a conventional polyurethane heated-spraying nozzle for admixing, heating, and spraying the polyurethane ingredients into the area to be filled in the first mounted tire.

FIG. 3B illustrates the second step, when a plurality of tires are being stacked to produce a floatation means of greater buoyancy than a single polyurethane-filled tire.

A primary utility of the present invention arises from several factors. One factor is the fact that this invention is consistent with good and desired ecology both from the standpoint of employing old tires which characteristically have in the past constituted a serious problem of disposal, as well as the fact that the structure such as illustrated in FIG. 1 having the floatation means spaced at significantly distant intervals to avoid the collection of floating debris. Together with the collection and further use of old tires, the cost of the floatation

means and/or platforms of the applicant's invention is very low, and a significant improvement over the cost of prior art floatation devices and platforms, as a result of the ready availability of large numbers of old tires, the sole significant cost being the cost of collection and transportation of the tires. The process, equipment, and the hollow mounting rod embedded within the polyurethane are all of simple structure and/or minimal cost. In addition to the cost factor, the use of old tires in water as bumpers and the like is evidence of the well known durability and toughness and resistance to corrosion, rot, and the like, all of these characteristics adding to the utility of the floatation device of this invention. The mere shape of the tires themselves and the simple process of making the floatation device of this invention lends to extreme flexibility in varying the number of tires employed, i.e., the thickness of the floatation means, as well as there being no significant limitations on the variations of design of the floatation platform. Another advantage of the particular shape of the polyurethane-filled tire and the hollow rod extending therethrough, together with subsequently inserted mounting rod for tying together upper and lower connecting structures, is that the resulting frame work when upper portions of a plurality of the floating means are connected and when a plurality of the lower portions of the floating means are interconnected is a series of "I" structure-beams sturdily and rigidly tying together upper and lower connecting structural networks between the plurality of floating means. As a result of the lower connecting structures and parallel with the upper portions of the floating means interconnected by a plurality of the vertical or upright bars therebetween, the downward bending of the upper deck of the platform — to compress the upper deck structure, and the consequent downward bending of the lower connecting structure — the lower connecting structure being stretched as a result of the weight carried on the upper deck, both are significantly reduced as compared for example to mere reliance on a sole upper structure network, for example.

The primary value of the one or more rubber tires is the protection of the floatation material such as the polyurethane, for example, from damage, from impact, and from uncontrolled growth to indeterminate shapes. Also the compacting of the growing foam within the tire casings during growth serves to impart greater strength to the polyurethane structure.

FIG. 1 discloses a plurality of separate stacks 1 of polyurethane-foam filled rubber tires 2a and 2b spaced at predetermined distant intervals with each anchored to an upper deck 3 by a bolt 4. The upper portions of the plurality of stacks are connected by a series of parallel beams such as beam 5 extending along the imaginary longitudinal axis 5a. Parallel to the beam 5 is a second beam 6 extending along the opposite edge of the deck structure mounted on top of a second series of aligned stacks. On top of the beams 5 and 6 are transverse beams 7a, 7b, 7c, 7d, 7e, 7f, and the like, on top of which the deck 3 is mounted. Similarly, the deck 3a is mounted on top of transverse beams 7g, 7h, and the like. By employing this structure of parallel beams such as 7e, 7f, and the like, there is accordingly produced a free space between parallel transverse beams through which slidible extension beams 8a and 8b may be inserted and anchored, for various purposes such as

securing to piling 9 or such as producing appropriate marina slips, or the like.

FIG. 2 illustrates a typical cross section of a preferred floatation device as taken along lines 2-2 of FIG. 1. Identifiable thereon are the securing bolt and nut 4 and 10, the tires 2aa and 2bb, the deck 3a, the transverse member 7h, and a longitudinal beam 10a. Additionally disclosed are the upper and lower pressure plates 11a, 11b, 11c, and 11d, each of which normally would be of square, triangular, or other irregular shape in order to anchor the respective plates within the foam. Also disclosed is the tubular connector 12 extending between the polyurethane-filled stacked-tires, centrally located typically as shown in FIG. 2, and lower connecting beams 10b and 10c.

FIG. 3A illustrates a tire casing 2aa placed on turntable 13 rotatably mounted on shaft 14 driven by motor 15 and held in a centered position by supports 16a and 16b with the plates 11a, 11b, 11c, and 11d screwed onto tubular member 12 centered by centering bolt 17 screwed into threaded female aperture 18, and polyurethane spray nozzle 19 including a heatable mixing chamber 20 into which separate polyurethane reactants are fed by tubes 21 and 22 from a source not illustrated. The FIG. 3A also discloses typically the admixed and heated polyurethane ingredients being sprayed with spray 23 falling within the tubular tire casing and within the overall enclosure.

FIG. 3B illustrates a second step of placing a second tire 2bb after the polyurethane is sprayed into tire 2aa has expanded to about level 24.

It is to be understood that there may be any number of tires stacked one on another and filled with polyurethane in the manner illustrated.

Another typical method would consist of one or more tires placed in an upright position, a hole cut in the upright flat surface thereof through the tread of a tire, the placing of enclosing barrier plates on either side of the tire to enclose the space of the interior of the tire casing with injecting concurrently a centering of the plates 11a, 11b, 11c, and 11d and the tubular member 12, and thereafter the injecting of or pouring of the ingredients necessary for the production of the polyurethane through the opening cut in the tread of each of the tires.

Although only two general methods have been described above, for the production of the individual polyurethane-filled tire and/or the filling of a stack of such tire casings, any convenient or other desired method may be employed for placing the tire casings into appropriate position, centering the tubular means in place and having the foam expand within the casings and around the tubular means in place.

Similarly, although polyurethane has repeatedly been referred to in the preceding disclosure, any convenient or desired closed cell foam or plastic may be employed together with or as a substitute for the discussed polyurethane.

By employing the invention as disclosed above, platforms in bodies of waters such as lakes, rivers, or the ocean, for example, may be employed as docks for small or large seagoing vessels, repair depots, or even heliports or airports.

Because of the low cost of production of the floating space frame and platform of this invention, after considerable wear and tear, the entire platform structure may be discarded without any significant economic loss

because of the small investment initially involved as well as the long term of usage due to the high degree of durability thereof.

The polyurethane, as is well known in the art, is conventionally produced by reacting isocyanate with a suitable conventional polyol. Conventional or desired proportions may be employed in conventional reactions. Similarly, other foam polymers of conventional or desired composition may be employed and produced by known reactions from known ingredients at known or desired proportions.

It is to be recognized that the above are intended to solely illustrate typical apparatus and methods and the resulting products and platforms of this invention, and are not intended to limit the scope of the invention unduly, the scope of this invention extending to all equivalents and substitutes as would be apparent to a person of ordinary skill. As to the process of FIGS. 3A and 3B, during the final foam expansion, a flat-faced barrier wall or a timber beam is placed over the opening to provide a future beam seat.

What is claimed is:

1. A process comprising: admixing plastic-producing ingredients; treating said plastic forming ingredients with conditions necessary for formation of said plastic composition; confining said admixed and treated ingredients within said outer-casing until said plastic composition is formed; embedding said upper plate and said lower plate within said plastic composition during the formation of said plastic composition; and connecting said upper and lower plates with said rod means, after said admixing placing the admixed ingredients into said outer casing within about 30 seconds after said admixing is initiated, said process further comprising first forming said plastic composition within a first tire, thereafter placing a second tire on top of the first tire and repeating the steps of admixing the necessary ingredients for the formation of the polyurethane and introducing the further admixed ingredients into said second tire and confining ingredients therein during the formation of the polyurethane plastic, and embodying the upper plate and at least the upper portion of the polyurethane plastic formed in the last-stacked uppermost polyurethane plastic-fill tire.

2. A process according to claim 1, including placing the bottom-most tire prior to said admixing and confining, onto a turntable, and including passing through separate conduits, said necessary plastic-forming ingredients through a heating area into a nozzle admixing chamber and spraying the admixed ingredients out of said common nozzle admixing chamber into respective tires in which the plastic composition is to be formed.

3. A process according to claim 1, including connecting a plurality of said stack upper portions together by said upper connecting structure and connecting together a plurality of said stack lower portions by said lower connecting structure.

4. A floatation device comprising a sub-combination comprising: at least one tough outer-casing substantially resistant to corrosion and water-rot when exposed to sea water environment over long periods of time, having an opening thereinto; a tough closed-cell substantially resilient plastic composition mounted within said outer-casing; said plastic composition-casing combination including an upper plate and a lower plate respectively mounted unitarily about centrally of a re-

spective upper face and a respective lower face thereof; said plastic composition-casing combination being lighter than water; a sturdy rod means extending between and substantially rigidly connecting said upper and lower plates; and connector means for substantially rigidly connecting said lower plate to at least one adjacent other structure and for substantially connecting said upper plate to said at least one adjacent other structure, said sub-combination including a plurality of said outer-casings each having said plastic composition mounted therein, in a stack thereof having top and bottom faces of adjacent ones of said stack being fused together by said plastic composition around said stack such that said plurality is unitary, said upper plate and upper face being at about the top face of said stack and said lower plate and lower face being at about the bottom face of said stack, said device further including said other structure, said other structure comprising a plurality of said sub-combinations, connected together by said connector means with separate ones of said sub-combination-plurality being spaced at predetermined intervals in a lattice network substantially along a common horizontal plane, said connector means including also a substantially rigid upper horizontally extending structure connecting said plurality together at about each stack's top face, and a substantially rigid lower horizontally extending structure connecting said plurality together at about each said stack's bottom face, said outer-casing comprising a tire, in which said plastic composition comprises polyurethane foam, in which said stack comprises at least two tires placed one on the other with adjacent sides substantially in contact with each other, and in which said upper horizontally extending structure consists essentially of a deck, said deck including three layers comprising a lower deck structure, an intermediate deck structure, and an upper deck structure, said lower deck structure being a plurality of parallel beams each extending between and connecting at least two adjacent spaced stacks at their respective top faces, said intermediate deck layer being a plurality of spaced supports extending along a common plane with their respective longitudinal axis extending at an angle to the longitudinal axis of the beams of the lower deck layer and connecting at least two of said parallel lower deck layer beam, said upper deck layer being a substantially continuous planar surface suitable for walking thereon, and said lower connecting structure including longitudinal and transverse beams.

5. A floatation device according to claim 4, including additional extension beams slidably supportable between adjacent parallel intermediate deck layer beams, between said lower deck layer and said upper deck layer, such that said slideable beams are slideable to positions extending sideward from said deck.

6. For a floatation device comprising a sub-combination comprising: at least one tough outer-

casing substantially resistant to corrosion and water-rot when exposed to sea water environment over long periods of time, having an opening thereinto; a tough closed-cell substantially resilient plastic composition mounted within said outer-casing; said plastic composition-casing combination including an upper plate and a lower plate respectively mounted unitarily about centrally of a respective upper face and a respective lower face thereof; said plastic composition-casing combination being lighter than water; a sturdy rod means extending between and substantially rigidly connecting said upper and lower plates; and connector means for substantially rigidly connecting said lower plate to at least one adjacent other structure and for substantially connecting said upper plate to said at least one adjacent other structure, a method of producing the floatation device comprising: admixing plastic-producing ingredients; treating said plastic forming ingredients with conditions necessary for formation of said plastic composition; confining said admixed and treated ingredients within said outer-casing until said plastic composition is formed; embedding said upper plate and said lower plate within said plastic composition during the formation of said plastic composition; and connecting said upper and lower plates with said rod means.

7. A process of producing a floatation device comprising a sub-combination which sub-combination comprises: at least one tough outer-casing substantially resistant to corrosion and waterrot when exposed to sea water environment over long periods of time, having an opening thereinto; a tough closed-cell substantially resilient plastic composition mounted within said outer-casing; said plastic composition-casing combination including an upper plate and a lower plate respectively mounted unitarily about centrally of a respective upper face and a respective lower face thereof; said plastic composition-casing combination being lighter than water; a sturdy rod means extending between and substantially rigidly connecting said upper and lower plates; and connector means for substantially rigidly connecting said lower plate to at least one adjacent other structure and for substantially connecting said upper plate to said at least one adjacent other structure, said process comprising placing a series of said outer casings, where each said outer casing is a tire, aligned flushly side-by-side set on their treads, clamping said tires between said opposing plates with one plate being flush at one end of said series and the opposing plate being flush at the opposite end of the series, securing said plates together, providing a through-opening in an upwardly-facing position in each of a plurality of tires of the series, and introducing and treating foam plastic-producing ingredients through each said through-opening.
